UNITED STATES PATENT OFFICE.

WILLIAM B. HOPWOOD, OF COLLEGE POINT, NEW YORK, ASSIGNOR TO THE BEACON FALLS RUBBER SHOE COMPANY, OF BEACON FALLS, CONNECTICUT, A CORPORATION OF MASSACHUSETTS.

SHOE SOLE.

Application filed September 29, 1926. Serial No. 138,405.

This invention relates to improvements in shoe soles. More particularly it relates to a shoe sole of rubber or similar material having an arch support, and is specifically designed 5 for embodiment on shoes of the type known as athletic shoes, although not limited to such use.

With shoes as previously constructed, there is solid support for the ball of the 10 foot and for the heel of the wearer, but there is little or no support for the arch of the foot. The shank of the shoe sole, as it has previously been constructed, is a thin strip of material held in spaced relation 15 from the floor and easily flexed downwardly by pressure.

It is an object of this invention to provide an improved construction at the shank 20 of a shoe sole whereby support is obtained at this point for the instep portion of the foot of the wearer. It is a further object to provide a shoe sole which is light in weight while having arch supporting properties.

25 Other objects will be apparent from the specification and from the drawings in which latter:

Fig. 1 is a side elevation of a shoe having the improved type of sole;

30 Fig. 2 is a bottom plan view of the shoe sole;

Fig. 3 is a transverse sectional view along the line 3—3 of Fig. 2 showing the hollow shank; and

35 Fig. 4 is a transverse sectional view along the line 4—4 of Fig. 3 showing the shank in cross section.

Referring to the drawings, Fig. 1 represents an athletic shoe provided with the 40 improved sole. The sole may be formed of rubber composition and is fastened to a canvas top 1 by a foxing 2 around the outside of the sole and the lower portion of the upper with a toe piece 3 acting as a further reinforcement.

The ball and heel portions of the sole are 45 provided with projections 4, at the apex of each of which is a recess forming a suction cup 5, this construction providing a sure grip on soft or smooth slippery surfaces. Between the heel and ball of the sole is a shank portion 6 which is plain and consid-

erably thinner than the remainder of the sole. Extending around the entire periphery of the sole is a rib 7 having a relatively 55 broad flat bearing surface. As shown in Fig. 3, this rib extends upwardly to about the height of the projections 4 but in the finished shoe, due to the curvature of the last, the projections 4 extend slightly beyond the rib 60 7 so as to allow compression of the projections and produce a suction grip. The rib 7 which is slightly widened, as shown at 8, where it extends around the shank portion of the sole, furnishes an external arch support 65 at this point for the foot of the wearer. As shown in Fig. 3, the rib portion 8 is substantially in the same horizontal plane as the balance of the rib 7, but in the completed shoe, due to the curvature of the last, the 70 arch supporting portion 8 of the rib is slightly curved upwardly, as shown in Fig. 1. When the weight of the wearer is placed upon the sole, the arch supporting portion 8 of the rib bends downwardly slightly until 75 it comes in contact with the floor or other surface, and it then acts to support the arch of the wearer's foot.

By constructing the sole with a thick wear 80 enduring rib extending lengthwise for the full length of the instep so that the rib engages the surface walked upon, the disadvantages pertinent to the instep suspended from the floor, as previously constructed, are eliminated. The arch of the foot of the 85 wearer is afforded support such as it would have if not clad in a shoe. At the same time the shoe is not made appreciably heavier and its flexibility is retained.

While the invention has been described as 90 applied to an athletic shoe it is contemplated to provide other types of shoes with a reinforcing rib at the instep thereof. If desired the rib need be positioned only at the instep and not extend throughout the length of the 95 shoe as described.

Having thus described my invention, what I claim and desire to protect by Letters Patent is:

1. As an article of manufacture, a shoe 100 sole having relatively thick ball and heel portions, a relatively thin shank portion, and a rib of uniform thickness extending around the margin of said sole, the portions of said

rib on each side of the shank being of greater width than the remaining portions thereof to form an external arch support.

2. A shoe sole comprising relatively thick ball and heel portions, a relatively thin shank portion connecting said ball and heel portions, and marginal ribs on said shank portion, the thickness of the combined rib and

shank portion being substantially the same as the thickness of said ball and heel portions. 10

Signed at College Point, L. I., county of Queens, and State of New York, this 20th day of September, 1926.

WILLIAM B. HOPWOOD.
